BLOCK MOLDING MACHINE

Andrew T. Johnson, Las Vegas, Nev.

Application June 3, 1947, Serial No. 752,119

5 Claims. (Cl. 25—45)

1

This invention relates to block molding machines, and more particularly to a machine for pressure-molding concrete building blocks.

A main object of the invention is to provide a novel and improved concrete block molding machine which is simple in construction, easy to operate and reliable in performance.

A further object of the invention is to provide an improved block molding machine of the hydraulic pressure type which is inexpensive to manufacture, sturdy in construction and wherein the dimensions and texture of the product can be accurately controlled.

Further objects and advantages of the invention will become apparent from the following description and claims, and from the accompanying drawings, wherein:

Figure 1 is a front elevational view, partly in cross-section of a building block molding machine constructed in accordance with the present invention.

Figure 2 is an enlarged side elevational view, partly in cross-section, of the top portion of the block molding machine of Figure 1.

Figure 3 is a top plan view of the main body of the machine of Figure 1 illustrating the means employed therein for securing the core supporting frame therein.

Figure 4 is an enlarged front elevational detail view of the mold filling box and its supporting table, as employed in the machine of Figure 1.

Figure 5 is a front elevational view of the machine of Figure 1 showing its connections to a source of hydraulic fluid and pressure generating means therefor as employed in the present invention.

Referring to the drawings, 11 comprises the frame of the machine, the frame consisting of longitudinal base channels 12 and transverse base channels 13 rigidly secured together to define a rectangular bottom support for the machine, the channel flanges being directed outwardly, corner posts 14 secured to the inner corners of said bottom support and rising vertically therefrom, and a top rectangular frame section comprising longitudinal channels 15, 15' and transverse channels 16 secured at its inner corners to the top portions of the posts 14. Connecting the bottom transverse channels 13 is a horizontal bottom plate member 17 on which is secured a pair of cylinders 18, 18'. Each cylinder has a top wall 19 which is formed at its center with a vertical bore 20. Slidably engaging the walls of each cylinder is a piston 21 having a

stem portion 22 vertically slidable in bore 20. Piston 21 and stem 22 are formed with a central vertical bore 23 in which is slidably positioned a plunger rod 24 formed at its top end with an enlarged head 25. Connected to the bottom wall of each cylinder 18 at its center is a fluid inlet conduit 26, and connected to the junction of said conduits is a common fluid supply pipe 27. Each cylinder is connected at its upper wall portion to a vent chamber 28 having an air vent tube 29 and a fluid overflow tube 30. Overflow tube 30 is connected to the fluid reservoir 31, shown in Figure 5.

The upper portion of bore 23 is formed with an annular groove 32 connected by a passage 33 in stem 22 to the lower outer portion of said stem, said passage 33 opening into the upper portion of the cylinder 18 when the parts are in the positions shown in Figure 1. A passage 34 in the top wall member 19 connects the intermediate portion of bore 20 with the top of the cylinder chamber 18 and is arranged so that when piston 21 is raised by fluid pressure to its uppermost position in said chamber, as determined by a stop shoulder 35 carried by said piston, the lower end of passage 33 registers with the upper end of passage 34. This by-passes any fluid which has leaked past plunger bar 24 back to the upper portion of the main cylinder chamber. A stop screw 36 is provided in the bottom wall of each cylinder 18 for adjusting the lowermost position of piston 21.

Overlying and supported on the enlarged heads, 25, 25', is a bar member 37 which is vertically movable, responsive to the upward movement of said heads and is guided in its upward movement by vertical threaded bars 38 secured to the opposing horizontal flanges of the upper and lower transverse channel 16 and 13 and being slidably received in notches 39 formed in the end portions of the bar member 37.

Stop nuts shown at 40 and 41 respectively limit the upward and downward movements of bar member 37, said stop nuts being threaded on the vertical bars 38 and being vertically adjustable thereon.

Secured in the top rectangular enclosure defined by the upper longitudinal channels 15, 15' and the upper side channels 16 is a rectangular box-like frame 42 which is open at its top and bottom and is provided with transverse partitions 43, 43' dividing the frame into three equal mold box compartments. The frame 42 is adjustably secured in position by respective front and side clamping plates 44 and 45 engaged by clamping

screws 46 threaded through the respective front channel 15 and right side channel 16.

Secured to the bottom of the frame 42 by longitudinal bar elements 47 are spaced core blocks 48, two such core blocks, being provided in each mold box compartment. Overlying the end portions of the bar elements in each mold box compartment and slidably fitting around the core blocks and inside the walls of the compartment is a push block 49. Overlying the push block is a 10 pallet 50 on which the moldable material is adapted to be deposited. Secured to the bottom of each push block 49 substantially centrally thereof and depending therefrom is a vertical push rod 51 provided at its bottom end with an adjustable stop screw 52. The push rods 51 slidably pass through a horizontal guide plate 53 secured to the frame 11, said guide plate having upstanding guide collars 54 encircling the respective push rods 51. Subadjacent the stop screws 52 is the pressure equalizing bar 37 against which the piston heads 25 bear upwardly when fluid under pressure is introduced into the cylinders 18. Bar 37 is freely vertically movable within the frame 11 and is formed with the guide notches 39, as above described, cooperating with the vertical guide bars 38.

Pivotedly secured to the top transverse side edge of the frame 11 by a transverse hinge pin 55 is a top cover plate 56 provided with a counter-weight 57 to facilitate opening the cover plate. Pivoted to the opposite free edge portion of the cover plate is a latch 58 adapted to hook under the top flange of the adjacent side channel 16 to lock the cover plate in closed position. The cover plate carries on its bottom surface pressure lugs 59 fitting around the core blocks 48 in the space between said blocks and the mold box walls.

Secured to the rear top longitudinal channel 15' by triangular gussets 60 is a rearwardly extending horizontal table plate 61 substantially flush with the top flange surfaces of the channels 15, 15'. The table plate is formed with parallel transverse guide channels 62, 62 and slidably engaged therein are the lateral ribs 63, 63 carried by a box member 64 which is thereby transversely slidable on table plate 61. Box member 64 has side handles 65, 65 for manipulating the box member backwardly and forwardly with respect to the guide channels 62, 62. The bottom and top of the box member 64 are open. In charging the mold box compartment, box member 64 is first positioned on table plate 61 in the position shown in Figure 2 and is filled with the moldable material. With the push rods 51 in depressed positions, as shown in Figure 1, the box member 64 is then moved forwardly until it overlies the mold box compartments, whereby the moldable material drops into said compartments. The box member 64 is then moved back rearwardly of its starting position, whereby excess moldable material is struck off from the top of the mold box compartments. The mold box compartments are then ready for the molding operation.

In molding the blocks, the cover member 56 is swung to closed position and latched therein. Lugs 59 act to tamp the moldable material downwardly somewhat preliminary to the actual application of molding pressure. With cover member 56 locked in closed position, fluid under pressure is admitted to cylinders 18 through conduits 26, causing the main pistons 21 to rise, upward force being transmitted at heads 25 to the equalizer bar

37 and thence to the push rods 51, causing the push blocks 49 to rise in the mold box compartments and to compress the moldable material contained therein.

As shown in Figure 5, 31 designates the fluid reservoir. A conduit 66 connects reservoir 31 to a pump 67. The outlet conduit 68 of said pump is connected through an accumulator tank 69 to a conduit 70. Conduit 70 is connected to conduit 21 through a valve 71 which is manually controlled by a valve rod 72. Also connected to conduit 21 is an exhaust pipe 73 opening in reservoir 31, said exhaust pipe including a valve 74 which is manually controlled by a valve rod 75. Connected ahead of valve 71 to conduit 70 is a conduit 76 opening into reservoir 31 and including a relief valve 77 adapted to open when the pressure in conduit 70 rises to a limit value substantially higher than the working pressure value. The conduit connecting tank 69 to conduit 70 includes a manual shut-off valve 78. A by-pass conduit 79 connects conduit 68 to conduit 70 and includes a manual shut-off valve 80. By closing either valve 80 or valve 78, either by-pass conduit 79 or accumulator tank 69 may be excluded from the fluid pressure line. When tank 69 is employed, it acts to accumulate a large amount of fluid under pressure in the fluid supply system and substantially eliminates pressure fluctuations in the fluid pressure line.

In order to compress the moldable material, as above described, valve 74 is closed and valve 71 is opened, so that fluid under pressure enters the cylinders 18. Piston 21 in each cylinder moves upwardly until shoulder 35 thereof abuts the top wall of the cylinder. At this point valve 71 is closed momentarily and cover member 56 is unlatched and raised to a vertical position, being held therein by the counter-weight 57. Valve 71 is again opened, and plunger 24 of each cylinder is forced upwardly by the additional fluid under pressure entering the cylinders. Equalizer bar 37 is moved upwardly until further upward movement thereof is prevented by the stop nuts 40. This elevates the push blocks 49 and raises the formed blocks out of the mold box compartments, the push blocks being finally in positions such as shown in Figure 2.

Secured to the front wall of the box member 64 is a forwardly projecting horizontal lug 81. To receive a new charge of moldable material, box member 64 is moved forwardly until its bottom forward edge portion 82 abuts the adjacent top edge portions of the push blocks 49. The lug 81 by this motion moves over the top surface of the push blocks and pushes the pallet members 50 carrying the finished blocks 83 forwardly so that the pallet members and finished blocks may be removed from the machine. When unloading is completed, valve 71 is closed and valve 74 is opened, allowing the fluid in the cylinders 18 to exhaust into the reservoir 31 and allowing the pistons therein to return to their starting positions and the push blocks 49 to drop back to their bottom positions in the mold box compartments. New pallets are then inserted thereon and the process may be repeated.

The machine is not limited to the specific mold boxes illustrated and described above. Any size and shape of mold box and corresponding pressure transmitting members therefor may be employed in place of the frame 42 and its associated pressure transmitting components.

The length of the power stroke and the block 75 raising stroke may be readily adjusted by respect-

tively adjusting the stop screws 36 and the stop nuts 40 and 41. The depression of equalizer member 13 is limited by the adjustment of lower stop nuts 41, thus controlling the amount of material that can be placed in the mold box compartments before compression.

By the above described adjustments the power stroke and the subsequent block ejection stroke of the respective pistons 21 and 24 can be controlled within very exact limits.

Accurate sizing is obtained on all exterior and interior surfaces of the finished blocks due to the smooth vertical surfaces employed on the mold box walls and cores and the polishing action produced on the blocks during the process of upward ejection of the blocks along said smooth vertical surfaces.

The equalizer bar 37 insures that the compressive load will be equally distributed on the heads 25 and that said heads will advance in unison during the compression stroke. If one piston advances faster than the other the bar 37 tilts and engages the edge portions of the piston heads 25. This causes the leading piston to immediately assume more than its normal proportion of load, and since both pistons are of equal size and are actuated by a common pressure source, the piston carrying the greater load will be retarded until the other piston advances to the point where the bar 37 will return to horizontal position across the wide faces of the piston heads. From this point the pistons will again advance in unison.

The use of the energy-storing accumulator tank 69 makes it possible to employ a relatively small capacity pump 67.

While a specific embodiment of a block molding machine has been disclosed in the foregoing description, it will be understood that various modifications within the spirit of the invention may occur to those skilled in the art. Therefore, it is intended that no limitations be placed on the invention other than as defined by the scope of the appended claims.

What is claimed is:

1. A pressure molding machine for forming building blocks comprising a rectangular box-like frame, a pair of cylinders secured vertically in the lower portion of the frame, a main piston in each cylinder, an auxiliary piston telescoped in said main piston and vertically slidable therein, the main piston having a stem portion slidably fitting the top wall of the cylinder, an enlarged head on the top end of each auxiliary piston, a bar member overlying the piston heads, means guiding said bar member for vertical movement, a mold box secured in the upper portion of the frame, an upwardly movable plunger slidably fitting said mold box, and a depending vertical push rod carried by said plunger and engaging the bar member at its bottom end.

2. A block molding machine comprising a rectangular box-like frame, a vertical cylinder secured in the lower portion of the frame, a main piston in said cylinder having a stem passing slidably through the top wall of said cylinder, an auxiliary piston telescoped in said main piston and stem and vertically slidable therein, an enlarged head on the top end of said auxiliary piston, a pressure transmitting member overlying said

head, a mold box secured in the upper portion of the frame, a releasable closure for the top of said mold box, an upwardly movable plunger slidably fitting said mold box and defining a bottom closure therefore, and a depending rod member carried by said plunger and engaged at its bottom end with said pressure-transmitting member.

3. A block molding machine comprising a rectangular box-like frame, a pair of vertical cylinders secured in the lower portion of said frame, a main piston in each cylinder having a stem passing slidably through the top wall of said cylinder, an auxiliary piston telescoped in each main piston and stem and vertically slidable therein, an enlarged head on the top end of each auxiliary piston, a tiltable bar supported on said enlarged heads, a mold box secured in the upper portion of the frame, a releasable top closure for said mold box carried by said frame, a vertically movable plunger slidably fitting said mold box and defining a bottom closure therefor, and a depending rod member rigidly secured to said plunger and engaging the tiltable bar at its bottom end.

4. A block molding machine comprising a rectangular box-like frame, a pair of vertical cylinders secured in the lower portion of said frame, a main piston in each cylinder having a stem passing slidably through the top wall of said cylinder, an auxiliary piston telescoped co-axially in each of said main pistons and vertically slidable therein, a tiltable bar supported on the top ends of the auxiliary pistons, means carried by the frame for guiding said tiltable bar for vertical movement, a mold box secured in the upper portion of the frame, a releasable top closure for said mold box pivotally secured at one end to a top edge of the frame, a vertically movable plunger slidably fitting said mold box and defining a bottom closure therefor and a depending rod member rigidly secured to said plunger and engaging the tiltable bar at its bottom end.

5. A block molding machine comprising a rectangular box-like frame, a pair of vertical cylinders secured in the lower portion of said frame, a main piston in each cylinder having a stem passing slidably through the top wall of said cylinder, an auxiliary piston telescoped coaxially in each of said main pistons and vertically slidable therein, a tiltable bar supported on the top ends of the auxiliary pistons, means carried by the frame for guiding said tiltable bar for vertical movement, said means being adapted to limit the range of vertical movement of said bar, a mold box secured in the upper portion of the frame, a top closure for said mold box hinged to a top edge of the frame, a vertically movable plunger slidably fitting said mold box and defining a bottom closure therefor, a depending rod member rigidly secured to said plunger and engaging the tiltable bar at its bottom end, a horizontal support carried by said frame adjacent the top edge of said mold box, a pair of parallel guide rails on said support, a shell member slidably engaged with said guide rails and slidable on said support to a position overlying the mold box, and a forwardly projecting horizontal flange carried at the forward wall of said shell member.
